TUMBLER

John P. Jorgenson, Wilmette, and Alfred G. Kling, Chicago, Ill., assignors to Kling Bros. Engineering Works, Chicago, Ill., a corporation of Illinois

Application February 24, 1944, Serial No. 523,654

5 Claims. (Cl. 34—133)

This invention relates to improvements in tumblers and more particularly to tumblers adapted for use in the laundry or dry cleaning industry.

In the usual type of tumbler there is a garment receiving cylinder having a foraminous periphery rotatable in an outer casing. In addition, the outer casing is provided with relatively complicated means for preheating air and for introducing said air into the rotatable cylinder. Suction hoods and conduits are also provided to remove the moisture laden air from the perforations in the periphery of the cylinder as the latter rotates. This type of construction utilizes a substantial amount of material and is expensive to manufacture and assemble. Furthermore, the heated air tends to travel to the periphery of the cylinder before it has extracted a maximum amount of moisture from the garments. As a result the drying operation is rendered relatively slow and inefficient.

It is a general object of the present invention to provide a tumbler wherein a novel and simple arrangement is utilized for causing effective circulation of heated air through the cylinder while the latter rotates, the heated air being so directed as to cause it to efficiently act upon the garments within the cylinder to extract the maximum amount of moisture therefrom.

A further object of the invention is to provide a cylindrical tumbler having a solid, unperforated peripheral wall, having a garment receiving opening at one end of the cylinder, heating means at the same end, and an air exhausting means at the opposite end from the heating means, there being novel means for conducting heated air into the drum and for causing said air to circulate effectively in the drum while the latter rotates.

A further object of the invention is to provide a construction as above described wherein there is an exhaust conduit positioned axially of the drum at one end thereof, and wherein the fixed heating means surrounds the garment receiving opening and surrounds a perforated annular flange which projects from the marginal edge of the garment receiving opening, said annular flange being rotatable with the drum.

A further object of the invention is to provide a construction as above described wherein the drum is rotatable in an outer casing, and wherein there is a fixed door in the front of the outer casing which is in registration with the garment receiving opening in the front end of the drum, the perforated annular flange surrounding the garment receiving opening of the drum having its projecting edge rotatable closely adjacent to the

periphery of the fixed door, and the heating means being positioned to surround said annular flange and being accommodated in the space between the front of the casing and the front of the drum.

5 Other objects of the invention are to provide a tumbler which is simple and inexpensive to manufacture, easy to assemble, and which is well adapted for the purpose described.

10 With the above and other objects in view the invention consists of the improved tumbler and all its parts and combinations as set forth in the claims and all equivalents thereof.

15 In the accompanying drawing illustrating one complete embodiment of the preferred form of the invention, in which the same reference numerals designate the same parts in all of the views:

20 Fig. 1 is a vertical sectional view taken axially through the cylinder approximately on the line —— of Fig. 2; and

Fig. 2 is a front view of the improved tumbler, part being broken away.

25 Referring more particularly to the drawing, the numeral 8 designates a suitable supporting frame having legs 9. Suitably supported on the base are rollers 10, two on each side, which are engageable in external tracks 11 on the periphery of a rotatable drum 12. The rollers not only serve to 30 drive the rotatable drum but also support the same in its rotating movement. The rollers may be driven by any suitable means. In the illustrated form of the invention there is a pulley 13 which is driven from an outside source and said pulley causes rotation of a shaft 14 for one set of 35 the rollers 10. Motion may be transmitted by means of an endless chain or by any other suitable means from the shaft 14 to the shaft 15 for the other set of rollers 10. Thus rotation of the 40 driven pulley 13 in a desired direction causes simultaneous rotation of the two sets of drum supporting rollers 10 and rotation of the drum 12. Any other suitable means may be utilized for driving and transmitting power to the rollers. 45 Furthermore, the rollers may be used merely as a rotatable support and the drum may be driven through any type of transmission desired.

50 The tumbler cylinder or drum 12 has an unperforated peripheral wall 16 and has a front wall 17 formed with a garment receiving opening 18. Surrounding the garment receiving opening 18 is an outwardly projecting annular flange 19. The flange 19 extends at an angle of approximately 45° and is formed with perforations 20.

The opposite end of the drum is preferably formed with a head 21 which is frusto-conical in shape and which is formed with an axially positioned neck 22 forming an air outlet opening 23. The outer edge of the neck 22 is preferably flanged outwardly as at 24. Within the drum at the same end is a partition 25 formed with perforations 26. The partition 25 separates the main chamber 27 of the drum from the small auxiliary chamber 28.

Suitably supported on the base frame 8 is an outer casing 29. This casing is suitably formed of sheet metal and substantially encloses the rotatable drum except that the casing is open at the bottom to admit air from beneath the device as indicated by the arrows in Fig. 1.

At the rear end of the device and supported on a bracket 28' is a suction fan assembly 30. This assembly includes a housing 31 which communicates through an opening 32 with the air opening 23 of the drum. Surrounding the opening 32 and projecting into the casing is an annular collar 33 having a right-angularly extending flange 34. Seated between the flange 34 of the collar 33 and the flange 24 of the drum neck 22 is a floating ring 35. Springs 36 normally urge the flange 34 and floating ring 35 into frictional engagement with the flange 24 of the drum neck. Thus the drum can rotate while preventing loss of gases at the joint 37. Within the housing 31 is a suction fan 38 suitably driven by an electric motor 39. The fan is adapted to cause discharge of moisture-laden gases through the discharge outlet 40.

At the front end of the drum casing 29 is a front sheet 41 formed with a center opening 42. The door 43 which is hinged to the front of the casing, as at 44, normally closes the opening 42. The door is preferably cup-shaped in cross section as shown in Fig. 1 to form an annular shoulder 45 which projects into the casing and within the projecting edge of the perforated flange 19. Thus when the drum is rotating, the projecting edge of the flange 19 will rotate around the annular shoulder 45 of the door. When the door 43 is opened the flange 19 will direct garments into the garment receiving opening 18 of the drum.

Positioned within the front space 46 between the front of the casing 29 and the front end 17 of the drum is a circular group of heating coils 47. Steam or other heating medium is admitted through an inlet 48 at the top into a header 49. From the header the steam flows in both directions through the individual tubes 50 which comprise the heating coil. These tubes are preferably equipped with heat radiating fins 51. The heating unit may also be formed with a bottom header 52 from which a discharge conduit 53 extends. Other types of heating units may be employed, the steam coils being shown by way of illustration.

In the use of the device, garments to be dried are loaded into the receiving opening 18 while the door 43 is open. These may be garments which have been dry-cleaned or laundered. The door 43 is then closed and the drum is rotated. In addition the electric motor 39 is operated to cause operation of the suction fan. As the cylinder rotates, longitudinal ribs 54 within the cylinder will carry the garments upwardly until gravity causes the garments to fall back to the bottom of the cylinder or drum. At the same time air from beneath the casing will be sucked into the bottom of the casing, as indicated by

the arrows in Fig. 1, and into the space 46 at the front of the casing. In this space the air will be heated by the heating coils and the heated air will then pass through the perforations 26 of the flange 19 and into the rotating drum. This heated air will then pass longitudinally through the interior of the drum, through the perforations 26 of the partition 25, through the opening 23 in the neck 22, and into the fan housing 31. The moisture-laden air will ultimately be discharged through the discharge conduit 40. This air will act effectively on the tumbling garments to contact all portions thereof and to extract moisture therefrom. It is to be noted that the present construction compels the heated air to travel the full length of the rotating drum. Thus the drying operation is speeded up and rendered more efficient.

Various changes and modifications may be made without departing from the spirit of the invention and all of such changes are contemplated as may come within the scope of the claims.

What we claim is:

1. A tumbler comprising a rotatable cylinder having a garment receiving opening in its front end, a fixed outer casing housing at least said front end of the cylinder and having an air admission opening, said casing having a front portion spaced from the front of the cylinder and provided with a garment receiving opening in alignment with the garment receiving opening of the cylinder, a door for closing said opening of the outer casing, an apertured annular flange surrounding the garment receiving opening of the rotatable cylinder and rotatable with the cylinder and projecting into the front space between the casing and front end of the cylinder, the front edge of said annular flange being closely adjacent to the periphery of the door opening of the casing, heating means positioned in said front space and surrounding said flange, and means including a fan for drawing air into the casing and for causing movement of said air radially along the exterior of the front end of the cylinder in said front space, past said heating means, and through the apertures in the annular flange into the garment receiving opening of the cylinder.
2. A tumbler comprising a rotatable cylinder having a garment receiving opening in its front end, a fixed outer casing housing at least said front end of the cylinder and having an air admission opening, said casing having a front portion spaced from the front of the cylinder and provided with a garment receiving opening in alignment with the garment receiving opening of the cylinder, a door for closing said opening of the outer casing having a peripheral portion forming an annular shoulder which projects into the casing when the door is closed, an apertured annular flange surrounding the garment receiving opening of the rotatable cylinder and rotatable with the cylinder and projecting into the front space between the casing and front end of the cylinder and having overlapping relationship with said annular shoulder of the door, heating means positioned in said front space and surrounded said flange, and means including a fan for drawing air into the casing and for causing movement of said air radially along the exterior of the front end of the cylinder in said front space, past said heating means, and through the apertures in the annular flange into the garment receiving opening of the cylinder.

3. A tumbler comprising a rotatable cylinder having a garment receiving opening in its front end and having an air outlet opening in its rear end, a fixed outer casing housing at least said front end of the cylinder and having an air admission opening, said casing having a front portion spaced from the front of the cylinder and provided with a garment receiving opening in alignment with the garment receiving opening of the cylinder, a door for closing said opening of the outer casing, an apertured annular flange surrounding the garment receiving opening of the rotatable cylinder and rotatable with the cylinder and projecting into the front space between the casing and front end of the cylinder, the front edge of said annular flange being closely adjacent to the periphery of the door opening of the casing, heating means positioned in said front space and surrounding said flange, and means including a fan for drawing air into the casing and for causing movement of said air radially along the exterior of the front end of the cylinder in said front space, past said heating means, through the apertures in the annular flange and longitudinally through the cylinder to said air outlet opening.

4. A tumbler comprising a rotatable cylinder having a garment receiving opening in its front end, a fixed outer casing housing at least said front end of the cylinder and having an air admission opening, said casing having a front portion spaced from the front of the cylinder and provided with a garment receiving opening in alignment with the garment receiving opening of the cylinder, a door for closing said opening of the outer casing, an apertured annular flange surrounding the garment receiving opening of the rotatable cylinder and rotatable with the cylinder and projecting into the front space between

5 the casing and front end of the cylinder, the front edge of said annular flange being closely adjacent to the periphery of the door opening of the casing, heating means positioned in said front space and surrounding said flange, and means including a fan for drawing air into the casing and for causing movement of said air radially along the exterior of the front end of the cylinder in said front space, past said heating means, through the apertures in the annular flange, and longitudinally through the cylinder.

5. A tumbler comprising a rotatable cylinder having a garment receiving opening in its front end, a fixed outer casing housing said front end of the cylinder and having an air admission opening, said casing having a front portion spaced from the front of the cylinder and provided with a garment receiving opening in alignment with the garment receiving opening of the cylinder, a door for closing said opening of the outer casing, an apertured annular flange which is frustoconical in shape surrounding the garment receiving opening of the rotatable cylinder and rotatable with the cylinder and projecting into 15 the front space between the casing and front end of the cylinder, the front edge of said annular flange being closely adjacent to the periphery of the door opening of the casing, heating means positioned in said front space and surrounding said flange, and means including a fan for drawing air into the casing and for causing movement of said air radially along the exterior of the front end of the cylinder in said front space, past said heating means, through 20 the apertures in the annular flange, and longitudinally through the cylinder.
